Attorney

Inventor

UNITED STATES PATENT OFFICE

EARL C. RIPLEY, OF SHERMAN, NEW YORK

YARN CLEANER.

Application filed April 20, 1929. Serial No. 356,658.

This invention relates to "slubbers" or yarn cleaners, that is, devices for removing "slubs", thickened portions or bad places in the yarn, from the yarn in spooling or winding machines, these devices being intended and acting to prevent any thickened portion or "slub" from passing through an aperture or passage through which the yarn is traveling so that the yarn or thread will be instantly stopped and the yarn or thread will break down, permitting the operator to break out the "slub" or thickened portion and retie and draw a knot in the yarn in the usual and well-known manner. All yarn cleaners of this character known to me require a separate apertured cleaning plate to be used for different classes of yarn or thread, that is, for cotton, silk, wool, etc., and many of these cleaners use a rotatably adjustable plate having therein a plurality of apertures of different diameters, one plate being used for cotton, another for woolens, or one plate being used for certain sizes of yarn and another for other sizes. Such yarn cleaners, while effective, are relatively costly to make and in order to adjust the plate, the machine must be stopped while the adjustment is being made and further the apertures have to be made of different diameters and, therefore, only a certain limited number of apertures can be used with any particular plate.

One of the objects of the present invention is to provide a yarn cleaner or "slubber" which is simple, relatively cheap to make, and particularly which is capable of being used with practically every class of yarn and which is adjustable very delicately to yarns of differing diameters.

A further object is to provide a yarn cleaner which is so constructed and adjustable that the manufacturer or his operative may control the character of the yarn being spooled and which will permit of being very delicately and nicely adjusted while the winding machine is running, which is not possible with any other yarn or thread cleaner known to me.

A further object is to provide a device of this character in which the adjustment is made by a fine screw so that an infinite num-

ber of adjustments may be made while the machine is running so that the character of the yarn may always be under the control of the manufacturer.

Another object is to reduce the wear on the 55 yarn and on the cleaner itself due to the passage of the yarn thereover.

Other objects will appear in the course of the following description.

My invention is illustrated in the accompanying drawings, wherein:—

Figure 1 is a front elevation of my improved yarn cleaner;

Figure 2 is a top plan view thereof;

Figure 3 is a transverse section of the device;

Figure 4 is an enlarged section through the bearings and arm, the screw being shown in elevation;

Figure 5 is an enlarged exaggerated longitudinal section of the grooved element, a section being taken along the line of the groove.

Referring to these drawings, 10 designates a base plate having upstanding ears 11 apertured at 12 for the passage of screws, this plate being formed adjacent the ears with integral bearings 13 having a longitudinally extending screw 14 which is mounted to rotate in these bearings. The screw at one end is provided with a head 15 and at the other end with a jam nut 16 whereby the screw may be held in any adjusted position, the head of the screw being provided with a nick whereby a screw-driver may be used for turning the screw. The thread on the screw is relatively fine and of very slow pitch.

Mounted upon the base 10 immediately in front of the screw is a plate 17 which projects out at right angles to the face of the base 10 and the upper face of this base is formed with a longitudinally extending yarn receiving groove 18 whose character will be more specifically stated later as the character of this groove is very important.

Spaced from the ends of the plate 17 are the porcelain guides 19 and 20. The guide 19 is supported slightly below the level of the entrance of the groove 18, the guide 20 being higher than the member 17, or level therewith.

Mounted upon the screw 14 is a yarn engag-

ing arm 21 of relatively hard metal, the inner end of this arm being screw-threaded for engagement by the screw 14 so that as the screw 14 is turned in one direction or the other, the arm 21 will be caused to travel in one direction or the other along the screw and over the plate 17. The arm 21 is capable of being turned down upon the upper face of the plate 17 or turned to a vertical position entirely away from the plate 17. Preferably the arm is formed of a steel stamping, the inner end of the arm being bent as at 22 to partially embrace the screw 14 and the inner face of this bent portion 22 is screw-threaded so as to constitute a nut. The bent portion 22 extends around the screw 14 sufficiently so as to hold the arm upon the screw in all positions of the arm. The rear extremity of the arm is formed with an angular lug 23 and mounted upon the back of the base 10 is a spring 24 having a length equal to the traverse of the arm 21, the upper margin of this spring being engaged beneath the lug 23. This spring thus yieldingly holds the arm 21 down on to the face of the plate 17 but the arm 21 may be turned upward into a vertical position and in this position, the spring will hold the arm 21 raised.

Whenever it is desired to adjust the arm 21 longitudinally of the plate 17, the screw 14 is turned and then is locked by the jam nut 16 and the arm is thus held firmly in position to which it has been adjusted and the arm, of course, is urged downward against the face of the plate 17 by means of the spring 24 as described.

The face of the plate 17, as will be seen from Figure 3, is so formed that the arm does not bear against that portion of the face of the plate 17 inward of the groove 18, but bears against the margin of the plate outward of the groove 18, this margin being very slightly raised as shown exaggeratedly in Figure 3. The groove 18 is of vital importance in my construction. This groove as will be seen from Figure 5 is tapered both as to width and depth from one end to the other and constitutes a channel along which the yarn α moves. This groove at its entrance end is large enough to receive the yarns of largest diameter, but at its other end, the groove is decreased so that it will receive only yarns of the very smallest diameter.

In the use of this device, the arm 21 is turned down over the face of the plate 17 and extends over the groove 18 so that the under face of the arm 21 and the wall of the groove constitute practically an aperture through which the yarn, of whatever coarseness or fineness it may be, runs freely under all circumstances, travelling through this aperture with a minimum degree of friction or wear. When, however, a "slub" or thickened portion is present in the yarn and strikes the arm 21, the movement of the yarn will be

stopped and the yarn will break, thus requiring as is usual, the operative to break out the "slub" or thickened portion and retie the ends of the yarn.

The arm 21 with the wall of the groove 18 constitutes the wall of an adjustable aperture through which the yarn to be cleaned passes and this aperture is adjustable to an infinity of diameters by adjusting the arm 21 along the plate 17 either toward one end of the plate or toward the other.

When the arm 21 is adjusted toward the large end of the groove 18, it is adapted for yarns of large diameter. When adjusted at the opposite end of the plate, it is adapted to clean yarns of the very smallest diameter and obviously between these two extremities the arm is adjustable to suit yarns of every possible diameter and of every possible character.

It will be seen that the operation of re-threading, as it may be called, is quickly and easily accomplished after the yarn has been broken out and the ends retied, because of the fact that the arm 21 is capable of being lifted up, and there is no necessity of inserting or threading the yarn through an aperture, particularly an extremely fine aperture. The yarn cannot possibly get out of the groove 18 or become unthreaded.

By the use of this device, the manufacturer has complete control over the yarn turned out as by adjusting the arm in one direction or the other, the diameter of the thickened portions of the yarn which may be allowed to pass is controlled. The adjustment may be made, as before stated, while the machine is running and the adjustment is so simple that any operator can readily make it.

While I have illustrated a particular embodiment of my invention which I have found extremely effective for the purpose designed, I do not wish to be limited to this embodiment as many changes or modifications might be made in the structure of the device without departing from the principle of the same as stated in the appended claims.

It is to be understood that the arm 21 touches on both sides of the groove 18, but that from the inside of the groove to the inside of the member 17, the arm does not quite touch so as to prevent any collection of fluff on the face of the plate 17 from holding the arm up. Further by raising the margin of the plate slightly on each side of the groove, it is possible to effectively decrease the depth of the groove by grinding the face of the plate. The entrance end of the groove constitutes a trumpet guiding the thread or yarn into the groove under all circumstances and preventing any breakage of the thread when an arm is snapped down.

I claim:

1. A yarn cleaner including an element having on its face a longitudinally extending

- yarn receiving tapering groove, and a coacting element adjustable longitudinally of the groove and bearing against the face of the groove or element.
- 5 2. A yarn cleaner including an element having on its face a yarn receiving groove, tapering longitudinally both in width and depth, and a coacting element bearing against the face of the plate and adjustable longitudinally of the groove and overlying it.
- 10 3. A yarn cleaner including an element having on its face a longitudinally tapering yarn receiving groove, and a member normally bearing against the face of the element shiftable on the element longitudinally of the groove and normally extending across it, said member being movable from a position extending across the groove.
- 15 4. A yarn cleaner including an element having on its face a longitudinally tapering yarn receiving groove, and a member resiliently urged against the face of said element and extending across the groove and shiftable on the element longitudinally of the groove.
- 20 5. A yarn cleaner including an element having on its face a longitudinally tapering yarn receiving groove and a member resiliently urged against the face of said element and extending across the groove and shiftable on the element longitudinally of the groove, said member being movable from over the groove.
- 25 6. A yarn cleaner including an element having on its face a longitudinally tapering yarn receiving groove, an adjusting screw extending parallel to the groove and a member having threaded engagement with the screw and normally bearing against the face of said element and extending at right angles to and across said groove.
- 30 7. A yarn cleaner including an element having on its face a longitudinally tapering yarn receiving groove, an adjusting screw extending parallel to the groove, and a member having threaded engagement with the screw and normally bearing against the face of said element and extending at right angles to and across said groove, said member being rotatable on the screw to a position removed from the groove.
- 35 8. A yarn cleaner including an element having on its face a longitudinally tapering yarn receiving groove, an adjusting screw extending parallel to the groove, a member having threaded engagement with the screw and normally bearing against the face of said element and extending at right angles to and across said groove, said member being rotatable on the screw to a position removed from the groove, and a spring urging the member against the face of the element.
- 40 9. A yarn cleaner including an element having on its face a longitudinally tapering yarn receiving groove, an adjusting screw extending parallel to the groove, a member having threaded engagement with the screw and normally bearing against the face of the element and extending at right angles to and across the groove, said member being rotatable on the screw to a position at right angles to the face of the element and extending across the groove, said member being normally bearing against the face of the element and extending at right angles to and across the groove, said member being rotatable on the screw to a position at right angles to the face of the element, and a spring normally urging the member against the face of the element, but holding the member raised from the face of the element when the member is turned to a position at right angles to the element.
- 45 10. A yarn cleaner including an element having on its face a longitudinally tapering yarn receiving groove, an adjusting screw extending parallel to the groove, a member having threaded engagement with the screw and normally bearing against the face of the element and extending across the groove, said member being rotatable on the screw from a position bearing against the face of the element to a position at right angles thereto, and a spring having a length equal to the length of travel of the member and bearing against the same and normally urging the member against the face of the element and holding the member in a raised position when the member is turned at right angles to the face of the element.
- 50 11. A yarn cleaner including a supporting base, an element mounted thereon and having on its upper face a longitudinally tapered yarn receiving groove, yarn guides mounted upon the base in spaced relation to the ends of said elements and guiding the yarn along said groove, an adjusting screw mounted upon said base parallel to the groove, a member having threaded engagement with the screw and normally bearing against the face of said element and extending transversely across the groove, said member being rotatable upon the screw into or out of a position at right angles to the face of the element, and resilient means normally urging said member against the face of the element in all positions of the member but yieldingly holding the member in a raised position when the member is turned at right angles to the face of the element.
- 55 12. A yarn cleaner, of the character described, comprising a base plate having spaced bearings, an element extending out from the base plate and being formed with a longitudinally tapering groove in its upper face, yarn guides carried by the base in spaced relation to the ends of said element, the guide at the large end of the element being disposed slightly below the face of the element, the guide at the opposite end of the element being disposed slightly above the face of the element, an adjusting screw mounted in said bearings, a member having threaded engagement with the screw, and normally bearing against the face of the element and extending across the groove, and resilient means urging said member against the face of the element but permitting the member to be turned up.

ward to a position at right angles to the face of the element and holding said member in this position.

13. A yarn cleaner including a base plate, having spaced bearings, an element mounted upon the base plate and extending out at right angles thereto, the upper face of the element being formed with a longitudinally tapering groove, yarn guides mounted upon the base plates at opposite ends of said element and adapted to guide the yarn along said groove, an adjusting screw mounted in said bearings, an arm normally bearing against the upper face of said element and extending across the groove, said arm at its rear end being bent to partially or wholly embrace the screw, said bent portion being threaded, the arm beyond said bent portion being formed to provide an outwardly extending lug, and a spring mounted upon the base plate and coextensive with the effective length of the screw, the upper end of the spring being bent outward to engage beneath said lug on the inner end of the arm whereby to hold the arm against the face of the element to permit the arm to be turned to a vertical position.

14. A yarn cleaner including an element having on its face a longitudinally extending tapering groove, the depth and width of said groove at any selected point being equal to the diameter of a certain predetermined grade of yarn, and a coacting member bearing against the face of said element and extending across the groove and longitudinally adjustable relative to the groove.

15. A yarn cleaner including an element having on its face a longitudinally extending tapering groove, the depth and width of said groove at any selected point being equal to the diameter of a certain predetermined grade of yarn, and a coacting member bearing against the face of said element and extending across the groove and longitudinally adjustable relative to the groove, the groove being disposed adjacent one edge of said element and said element between the groove and the adjacent edge of the element being raised higher than the remainder of the face of the element whereby said member will bear against the relatively narrow raised portion of the element.

In testimony whereof I hereunto affix my signature.

EARL C. RIPLEY.
